[57] CLAIM

The ornamental design for an artificial fishing lure, as shown and described.

DESCRIPTION

FIG. 1 is a perspective view of another embodiment of the artificial fishing lure of the present invention;

FIG. 2 is a side elevation of the artificial fishing lure of FIG. 1;

FIG. 3 is a plan view of the artificial fishing lure of FIG. 1;

FIG. 4 is a bottom view of the artificial fishing lure of FIG. 1;

FIG. 5 is a front elevation of the artificial fishing lure of FIG. 1;

FIG. 6 is a transverse sectional view of the artificial fishing lure taken on line 6—6 of FIG. 1 showing the shape of the body of the lure in the central portion thereof;

FIG. 7 is a rear elevation of the artificial fishing lure of FIG. 1; and

FIG. 8 is a perspective view of the artificial fishing lure of FIG. 1 shown in an inverted position.
